FILLER VALVE

George L. N. Meyer, Milwaukee, Wis., assignor to
 Geo. J. Meyer Manufacturing Company,
 Cudahy, Wis., a corporation of Wisconsin

Application March 24, 1949, Serial No. 83,261

6 Claims. (Cl. 226—111)

1

This invention relates to filler valves and more particularly to a filler valve adapted to supply bottles or the like with liquids containing particles of solid matter.

Some trouble has been experienced in filling bottles on machines employing valves with screens to stop the flow of liquid upon equalization of pressure above and below the valve due to the pulp clogging the screen and either impeding or completely stopping the flow of the liquid.

It is an object of the present invention to provide a counter-pressure filler valve which will not become clogged when used on filling machines filling pulp drinks.

Another object is to provide a suitable counter-pressure filler valve for use with pulp drinks or other liquids containing solid particles.

A further object is to provide a counter-pressure filler valve which will be less subject to clogging than those now in use.

A further object is to provide a counter-pressure filler valve for pulp drinks or the like which will stop the flow of beverages when the pressures are equalized above and below the valve.

Still further objects will become apparent upon considering the following specification which when taken in conjunction with the accompanying drawings illustrate a preferred form of the invention, together with a modification thereof.

In the drawings:

Fig. 1 is a vertical cross-sectional view thru a filler valve showing the improved valve element.

Fig. 2 is an enlarged cross-section similar to Fig. 1 but showing the liquid valve element.

Fig. 3 is a transverse cross-sectional view of the liquid valve element, and is a cross-section taken on the line 3—3 of Fig. 1.

Figs. 4, 5 and 6 are views similar to Figs. 1, 2 and 3 respectively, but showing a modified form of the invention.

Referring to the drawings and more particularly to the form of the invention shown in Figs. 1, 2 and 3, the filling machine comprises a filler bowl 10 adapted to rotate about an axis (not shown), the bowl having a plurality of spaced apertures 12 therein in which are mounted filler valves, generally designated 14.

A beverage to be supplied to the bottles 15 is maintained at a predetermined level 16 in the filler bowl by means of a float controlled valve (not shown), the area above the liquid being subjected to counter pressure gas.

The valve 14 comprises a cage 18 having a closed cylindrical wall 20 and an open top 21 thru which liquid enters the cage 18. The cage 18 is received in the aperture 12 in the bowl 10 and is maintained on a shoulder 21 in the opening 12 by a clamp 23 which presses upwardly to

retain a valve seat 25 in the cage and simultaneously to retain the cage 18 in the aperture 12.

A liquid valve element 28 is mounted in the cage 18 and has a plurality of wings 30 forming a spider which contact the cylindrical walls 20 of the cage to center and guide the valve element 28 accurately in its vertical movement. The valve element 28 has a resilient seal 32 at its lower end which seats on the valve seat 25 to prevent the passage of liquid thru the valve when the valve is closed.

For further details of the seal 32 see the co-pending application of George L. N. Meyer, Serial No. 623,240 filed October 19, 1945.

15 An annular horizontal ring 35 is secured at its inner periphery to the valve element 28 and projects outwardly to a point adjacent the inside wall of the cylindrical walls 20 of the cage 18. The ring or disc 35 thus extends between the cage 18 and the valve element 28. The space between outer edge of the ring 35 and the inner cylindrical wall 20 of the cage 18 forms a long narrow passage or foramen 37 thru which liquid must pass in going thru the valve.

20 25 A vent tube 38 is secured in the upper end of the valve element 28 and passes upwardly thru the liquid in the bowl 10 and into the gaseous counterpressure gas above the liquid. The control of gas thru the vent tube 38 is effected by a gas control valve 40 which is opened mechanically by means of a lever 42 actuated by a cam follower 43. The valve 40 is maintained open by a spring 44.

25 30 The vent tube 38 has an extension 45 which is secured to the bottom of the valve element 28 and communicates with the vent tube 38 thru an aperture 46 in the valve element 28. The vent tube 45 extends downwardly into the bottle 15 for the passage of gas the outer surface of the tube serving to guide the liquid downwardly and off a spreader element 47 onto the inner surface of the bottle 15, thus preventing splashing and agitation of the beverage.

35 40 The vent stem 38 has a cylindrical guide plunger 50 fixed thereto which operates in a guide cylinder 51 supported from the top of the cage 18 by arms 52. The cylinder 51 guides the upper end of the vent stem 38 so that the entire valve element moves vertically.

45 50 A spring 54 is seated in a recess in the top of the valve cage and bears against the bottom of the plunger 50 to constantly urge the liquid valve element 28 into open position, the valve remaining closed normally by pressure of the liquid and counter pressure gas.

55 60 The clamp 23 is provided with a vertical cylindrical opening which receives a rubber sealing ring 55. For further details of the rubber sealing ring 55 see the co-pending application of Geo. L. N. Meyer, Serial No. 762,931 filed July 23, 1947.

The modification of the invention shown in Figs. 4, 5 and 6 uses similar numbers to designate parts identical to corresponding parts of the form of the invention shown in Figs. 1, 2 and 3, and description of such parts is omitted to eliminate undue duplication.

In the modification of the invention shown in Figs. 4, 5 and 6 the annular ring 55 (Figs. 1, 2 and 3) is replaced by an annular cup 60. The cup 60 comprises an annular ring 62 (best seen in Figs. 4 and 5) secured at its inner periphery to the liquid valve element 28 and extending outwardly and terminating in an upstanding annular collar 63 which lies closely adjacent the inner cylindrical wall 20 of the cage 18. Arcuate apertures 65 are provided for the passage of liquid past the valve element 28. The passages 65 are long and narrow to form slits or foramen.

In other respects the valve shown in Figs. 4, 5 and 6 is identical to the valve shown in Figs. 1, 2 and 3.

Operation

In operation, the filler bowl 10 is filled with a liquid beverage until the level of the liquid rises to the level 16, which is well above the level of the liquid valve 28 but below the air valve 40. The filling machine may then be started, bottles 15 placed on the stirrups (not shown) and raised into sealing engagement with the sealing ring 55. When the neck of the bottle 15 is in sealing engagement, a cam (not shown) contacts the cam follower 43 actuating the lever 42 to open the gas control valve 40 permitting counterpressure gas to flow downward thru the tubes 38 and 45 and the passage 46 into the bottle 15.

When the pressure within the bottle 15 is substantially equal to the pressure downwardly of the liquid, the spring 54 overcomes the liquid pressure on the valve 28 and raises that valve off its seat 32, permitting the beverage to flow downwardly thru the valve cage 18, thru the foramen 37 past the valve 28 and is deflected off the vent tube 45 by the spreader element.

As the beverage flows into the bottle 15 the counter-pressure gas in the bottle escapes thru the vent tubes 45 and 38 and returns to the top of the bowl. When the liquid in the bottle rises above the bottom of the vent tube 45 gas can no longer escape from the top of the bottle 15 and hence pressure builds up in the top of the bottle until the pressure of the liquid down is balanced by the pressure of the gas up.

When the pressures up and down balance the liquid is prevented from flowing down since it must first pass thru the narrow slits on foramen 37 or 65. The natural surface tension across the foramen prevents the flow of liquid downward at this time and thus stops the filling action.

As the bottles 15 approach the unloading station the valves 28 and 40 are both closed mechanically by the cam follower 43 and excess gas in the top of the bottle drawn off thru a snifter valve (not shown).

The bottle is then lowered out of contact with the seal 55 and the bottle removed for capping.

It will be realized that the hereinbefore described forms of the invention are to be taken merely as preferred embodiments thereof, and that various changes in size, shape and arrangement of parts may be made without departing from the spirit of the invention or the scope of the subjoined claims.

That which is claimed as new and is desired

to be secured by United States Letters Patent is:

1. A filler valve of the character described comprising, a cylindrical valve cage, a liquid valve seat at the lower end of said cage, a valve seated on said seat and an annular disc having its inner periphery lying adjacent the inner cylindrical surface of said cage to provide a restricted passage for liquid between the cage and the disc.

2. A filler valve adapted to control the flow of beverage thru an opening in a counter-pressure filler comprising, a valve seat in said opening, a valve element adapted to cover said seat to control the flow of liquid thru said opening, a tubular valve cage surrounding said opening, said cage having an opening for the entrance of liquid above the lower end of the valve when the valve is in raised position, and an annular ring secured to the periphery of the valve and extending outwardly to a point adjacent the inner periphery of the cage to form a narrow elongated passage for the liquid.

3. A filler valve adapted to control the flow of a beverage thru an opening in a counter-pressure filler comprising, a valve seat surrounding said opening, a valve element seated on said seat, a foraminous element fixed to and movable with said valve and adapted to stop the flow of liquid downwardly therethru upon equalization of pressure up and down at the valve.

4. A filler valve adapted to control the flow of a beverage thru an opening in a counter-pressure filler comprising, a valve seat surrounding said opening, a valve cage having a cylindrical inner wall, a valve in said cage adapted to seat on said valve seat to close said opening a cup shaped member fixed concentrically to valve and having the upturned rim of said cup closely adjacent said cylindrical wall, the flat bottom of said cup having a foramen adapted to prevent the passage of liquid downwardly upon equalization of the pressures up and down at the valve.

5. A filler valve adapted to control the flow of beverage from a counter-pressure filler bowl to a container to be filled comprising, a cylindrical valve cage, a liquid valve seat at the lower end of said cage, and a disc mounted between said cage and said valve and providing a foraminous element for the passage of beverage between said valve cage and said valve.

6. A filler valve of the character described comprising, a cylindrical valve cage having an opening for the passage of liquid through the lower end thereof, a valve seat surrounding said opening, a valve mounted in said valve cage, and a disc extending between the inner surface of said cage and said valve above said seat and providing a foramen for the passage of liquid through said valve cage and past said valve.
